UNITED STATES PATENT OFFICE

CHARLES H. BROWN, OF FLUSHING, NEW YORK

DESIGN FOR A SHOE

Application filed December 30, 1929. Serial No. 33,974. Term of patent 14 years.

To all whom it may concern:

Be it known that I, CHARLES H. BROWN, a citizen of the United States, residing at Flushing, in the county of Queens and State of New York, have invented a new, original, and ornamental Design for Shoes, of which the following is a specification, reference being had to the accompanying drawing, forming part thereof, and in which—

I claim:

The ornamental design for a shoe, as shown.

CHARLES H. BROWN.
